UNITED STATES PATENT OFFICE.

MORRIS B. CARROLL, OF LYNN, MASSACHUSETTS, ASSIGNEE TO GENERAL ELECTRIC COMPANY, A CORPORATION OF NEW YORK.

GOVERNING MECHANISM.

1,120,999.

Specification of Letters Patent. Patented Dec. 15, 1914.

Application filed November 24, 1913. Serial No. 802,648.

To all whom it may concern:

Be it known that I, MORRIS B. CARROLL, a citizen of the United States, residing at Lynn, county of Essex, State of Massachusetts, have invented certain new and useful Improvements in Governing Mechanism, of which the following is a specification.

My invention relates to elastic fluid turbines designed to be primarily driven by low pressure steam, as the exhaust from high pressure non-condensing prime movers, and is applicable to such turbines of either the low pressure or mixed pressure type.

My invention relates particularly to a governing mechanism for controlling the supply of motive fluid to such turbines, one object being to provide a governing mechanism which is responsive to the speed of or load on the turbine, to a condition of the motive fluid at the inlet of the turbine, and to the exhaust pressure.

In installations where the efficiency of the prime mover is improved by a reduction in the back pressure, it is advantageous when the load on the turbine is light to by-pass the excess of exhaust steam to the condenser, thereby giving the prime mover the benefit of a lower exhaust pressure. A further feature of my invention consists in the application of my governing mechanism to a turbine provided with such a by-pass.

Other objects and advantages of my invention will be pointed out hereinafter.

Referring to the drawing wherein I have illustrated by way of example certain forms which my invention may take, Figure 1 is a diagrammatic view of a turbine to which my improved governing mechanism has been applied and which is shown as connected to receive the exhaust from a high pressure prime mover; Fig. 2 is an enlarged view of a diagrammatic nature showing a turbine embodying my invention; Fig. 3 is a detail view of a modification.

The prime mover 1, here shown as being a high pressure reciprocating engine, receiving its supply of high pressure steam through the conduit 2, has its exhaust conduit 3 connected to the turbine 4. This turbine may be, as before stated, either a low pressure or a mixed pressure machine and

in either case is provided with a high pressure valve mechanism 5 through which live steam may be fed to the turbine from conduit 6. The turbine is shown as exhausting through conduit 7 into a suitable condenser 8. Connecting the conduits 3 and 7 is a by-pass 9 in which is arranged a suitable valve 10. The valve 10 is operated through rack 11, pinion 11 and rod 12 by the piston 13 of a hydraulic motor 14. The piston 13 also operates the high pressure valve mechanism 5 through the rod 15. The connections of the piston to valve 10 and valve mechanism 5 are such that the valve mechanism 5 does not become operative to admit live steam to the turbine until valve 10 is substantially closed. The hydraulic motor is controlled by an ordinary pilot valve 16 provided with a pressure inlet 16^a and pressure outlets 16^b and having its stem 17 attached at an intermediate point to the floating lever 18. This floating lever has one end attached to the speed governor 19 and the other end through link 20 and lever 21 to the rod 15. The arrangement of governing mechanism for the valve 10 and valve mechanism 5 so far described constitutes a well known form embodying a follow-up device, the operation of which is well known.

In connection with the speed governor arrangement just described, I provide means responsive to a condition of the supply of low pressure steam for affecting the hydraulic motor mechanism which means may take the form of either a pressure responsive device, a flow responsive device or a combination of the two. The provision of such a means is of particular advantage in connection with a turbine installation having a by-pass as shown in that it provides for a close and efficient regulation.

In cases where the condenser vacuum varies it is also of advantage to have the controlling means for the motive fluid responsive to such variations since any change in this vacuum will affect the operation of the machine, and my invention contemplates the provision of means responsive to such variations.

In Fig. 2, 22 is a diaphragm, the interior of which is subjected to the pressure of the fluid supply in conduit 3. A stem 23 carried by this diaphragm is pivoted to one end of floating lever 24, the opposite end of

which is adjustably pivoted in the connector 25. At an intermediate point lever 24 is attached to lever 21 by link 26. By this arrangement any movement of diaphragm 22 is transmitted through the parts 23, 24, 26, 21, 20, 18 and 17 to the pilot valve 16 controlling the hydraulic motor 14. At 27 is shown a second diaphragm, the interior of which is in communication with the conduit 7 leading to condenser 8. The stem 28 of this diaphragm is pivoted to one end of a lever 29 supported at an intermediate point by arm 30. The other end of lever 29 adjustably engages the connector 25. An upward movement of diaphragm 27 will thus lower the left hand end of lever 29 thereby permitting lever 24 to move downward, the end of stem 23 acting as the pivot point. By this movement the pilot valve is affected 15 in the same manner as by a contraction of diaphragm 22, it being evident that an increase in vacuum pressure produces the same general effect on the turbine as would a decrease in the admission pressure. These 20 corresponding effects are not equal for equal changes in pressure but are, however, proportioned to each other. A contraction of diaphragm 27 operates oppositely to that just explained as will be obvious. In the 25 arrangement as shown in Fig. 2, it will be evident that the admission of fluid pressure is controlled by the speed governor and by the pressures in the inlet conduit and the condenser; *i. e.* by the drop in pressure 30 across the machine.

In place of the pressure responsive device as shown at 22, in Fig. 2, I may use a suitable flow responsive device. One form of such device is shown in Fig. 3. In this 40 figure 24' corresponds to the lever 24 of Fig. 2, and through the stem 23' is connected to the float 22', here shown as a disk. This float is arranged in the inlet conduit 3' and is responsive to the rate of flow 45 through the same.

While I have shown the fluid admission mechanism when applied to a turbine provided with a by-pass as being under the control of both a condition of the fluid supply and the vacuum pressure, it will be clear that if desired and conditions permitted either one or the other control might be omitted.

In accordance with the provisions of the 55 patent statutes, I have described the principle of operation of my invention, together with the apparatus which I now consider to represent the best embodiment thereof; but I desire to have it understood that the 60 apparatus shown is only illustrative, and that the invention can be carried out by other means.

What I claim as new and desire to secure by Letters Patent of the United States, is:—

65 1. The combination with a turbine having

a conduit for supplying motive fluid thereto and an exhaust conduit, of a by-pass leading from said supply conduit, valve means in the by-pass for controlling the effective area thereof, a speed responsive device, a device responsive to the pressure in the supply conduit, and means connecting said device to the valve means for controlling the same. 70

2. The combination with a turbine having a conduit supplying motive fluid thereto, and an exhaust conduit, of a by-pass leading from said supply conduit, valve means therein for controlling the effective area of said by-pass, a governor, a device responsive to the condition of the motive fluid supplied to said turbine, and means connecting said governor and said device to the valve means. 75

3. The combination with a turbine having a conduit for supplying motive fluid thereto and an exhaust conduit, of a by-pass leading from the supply conduit, valve means for controlling the effective area of said by-pass, and means controlled by both the speed of the turbine and the drop in pressure across said turbine for controlling said valve means. 80

4. The combination with a turbine having a conduit for supplying motive fluid thereto and an exhaust conduit, of a by-pass leading from said supply conduit, valve means for controlling the effective area of said by-pass, a speed governor for controlling said valve means, and means responsive to the drop in pressure across said turbine for also controlling said valve means. 90

5. The combination with a turbine having a conduit for supplying motive fluid thereto and an exhaust conduit, of a by-pass connecting the supply conduit to the exhaust conduit, valve means for controlling the effective area of said by-pass, a speed governor for controlling said valve means, and means responsive to the drop in pressure across said turbine for also controlling said valve means. 100

6. The combination with a turbine having a conduit for supplying motive fluid thereto and an exhaust conduit, of a by-pass connecting the supply conduit to the exhaust conduit, valve means for controlling the effective area of said by-pass, and means controlled by the speed of the turbine, a condition of the motive fluid supplied to said turbine and the pressure in said exhaust conduit for controlling said valve means. 115

7. The combination with a turbine having a conduit for supplying motive fluid thereto and an exhaust conduit, of a by-pass leading from said supply conduit, valve means for controlling the effective area of said by-pass, and means controlled by the speed of the turbine and by the pressure in said exhaust for controlling said valve means. 125

8. In combination, a high pressure engine, 130

a low pressure turbine, a conduit for conveying the exhaust from the high pressure engine to said turbine, an exhaust conduit for the turbine, a by-pass leading from the first named conduit, valve means for admitting high pressure steam to said turbine, valve means for controlling the effective area of said by-pass, and means controlled by the speed of said turbine and by the drop

in pressure across said turbine for controlling both of said valve means.

In witness whereof, I have hereunto set my hand this 20th day of November, 1913.

MORRIS B. CARROLL.
